UNITED STATES PATENT OFFICE.

WILSON HEMINGWAY, JR., OF PHILADELPHIA, PENNSYLVANIA, ASSIGNOR TO THE ELECTROLOCK MANUFACTURING COMPANY, OF VICKSBURG, MISSISSIPPI, A CORPORATION OF MISSISSIPPI.

LOCK OR LOCKING DEVICE.

Application filed September 10, 1925. Serial No. 55,518.

This invention has reference to locks or locking devices but relates more particularly to ignition lock switches as used on automobiles and motor boats.

5 One purpose or object of the invention is to provide means of novel construction which make it practically impossible for the lock releasing key to be inadvertently left in the lock at any time.

10 It also is a purpose or object of the invention to provide means of novel construction whereby when the releasing key has been actuated to release the lock mechanism to close or permit closing of the switch to close 15 the ignition circuit the said lock mechanism cannot be returned to locked position to open the said switch without first removing said key.

Another object of the invention is to provide 20 means of novel construction whereby, after the release of the lock mechanism by a releasing key and the removal of the key from the lock, it is impractical to reinsert the key into the lock until after the locking 25 mechanism has been returned to locked position.

To these ends the invention in one practical embodiment thereof consists essentially in the provision of a switch having a key 30 releasable lock for securing the switch contacts in circuit breaking position and restraining means in the form of a novel key-hole guard arranged to compel removal of the key from the lock immediately on release 35 of the latter as a necessary precedent to shifting the switch contacts from circuit breaking to circuit closing position. The aforesaid restraining means is displaceable to an inoperative position on removal 40 of the key from the lock so as to permit actuation of the switch contacts to circuit closing position but when so displaced the key hole guard portion thereof is positioned to prevent reinsertion of the key in the lock 45 until the switch contacts have been returned to and locked in the circuit breaking position.

Other purposes and advantages of the invention as well as the details of construction and the arrangement of parts constituting the preferred embodiment disclosed herein will be more readily apparent from the following detailed description and accompanying drawings, in which,

Figure 1 is a view of the front end of the 55 lock as it will appear in the locked position of the switch with the parts arranged for the insertion of the key.

Figure 2 is a longitudinal sectional view 60 through the casing and other parts of the switch, certain elements being shown in elevation.

Figures 3, 5 and 7 are views similar to Figure 1 but showing the parts in different 65 positions.

Figures 4, 6 and 8 are views similar to Figure 2 but showing the parts in the different positions to which they will be moved during unlocking and relocking of the 70 switch.

The switch to which the present invention is applied is fully disclosed in my co-pending application Serial Number 709,695, filed Apr. 28, 1924, and hence, for present purposes, will be briefly treated as follows: The 75 casing 5 houses therein a pair of relatively spaced blocks 6 and 7 which are composed of any suitable insulating material and formed with aligned guide bores 8 and 9 in which are arranged the ends of a reciprocable 80 stem 10 having its central portion shaped to present inclined surfaces 11 and 12 sloping downwardly from a central ridge 13. The block 7 carries a pair of spaced stationary contacts 14 which constitute terminals 85 of an ignition circuit (not shown) and are adapted to be bridged at times by a movable contact 15 encircling the stem 10. This contact 15 consists of a ring shaped casing open along its inner periphery and housing a circular coiled spring 16 which is always in gripping engagement with the stem 10.

In the open position of the switch the aforementioned parts are arranged as in Figure 2 with the contact 15 lying at the 95 left of ridge 13 and against the block 6. When it is desired to close the switch, stem 10 is moved to the left, as hereinafter described, until ridge 13 passes through coil spring 16 at which time the pressure exerted 100 by the spring 16 on the inclined surface 12 will cause the movable contact 15 to snap to the right and into engagement with the contacts 14. To open the switch the stem 10 is moved to the right from the position 105 shown in Figure 6 until the inclined surface 11 is brought into engagement with spring 16 at which time the movable contact 15 will

be caused to snap back to the position shown in Figure 2.

The stem 10 is moved to the right and locked in the position shown in Figure 2 through the medium of a lock barrel 17 slidably mounted in one end of the casing 5 and bearing against one terminal of the stem. This barrel carries a suitable lock mechanism including a spring projected bolt 18 adapted to automatically enter an opening 19 of the casing when the barrel is moved inwardly to the position shown in Figure 2. The sliding movement of the lock barrel relative to the casing is limited by a stop pin 20 projecting inwardly from the wall of the casing 5 and having its inner extremity disposed in a recess 21 formed in and extending longitudinally of the barrel 17. When the bolt 18 of the lock mechanism is retracted from the opening 19 movement of the stem 10 from the position shown in Figure 2 to that shown in Figure 6 is effected automatically through the agency of a spring 22 having one end seated in a pocket 23 formed in the stem 10 and the other end bearing against the inner end wall of the guide bore 9.

The present invention, as adapted to the switch described in the foregoing, consists of a switch control device 24 in the form of a sleeve which encircles the lock barrel 17 and is rotatable thereon. The outer end of the sleeve is closed as indicated at 25 to provide a key-hole guard formed with an opening 26 adapted to register at times with a key-hole 27 formed in the lock barrel 17 for the reception of a suitable key (not shown) by which the bolt 18 is retracted from the opening 19. Sleeve 24 is formed with a circumferentially extending slot 28 through which extends the aforesaid stop pin 20 of the casing 5. At one end of this slot is formed with an extension 29 projecting toward the inner end of the sleeve and made of a transverse width substantially equal to the width of the recess 21 with which said extension is adapted at times to register. A sufficient portion of the inner edge of the sleeve is cut away as indicated at 30 to permit the sleeve to have the requisite turning movement on the lock barrel without interference by the bolt 18.

In describing the operation of the switch with my invention applied thereto we will assume the switch to be in the locked position shown in Figures 1 and 2. In this position of the switch the contact 15 is separated from the contacts 14 with the result that the ignition circuit is broken. The switch control sleeve 24 is so positioned that the opening 27 at the outer end of the sleeve is arranged directly over the key-hole 27 while the extension 29 of the sleeve slot 28 is disposed at the side of the recess 21 remote from the bolt 18. To close the switch a

suitable key is inserted in the keyhole to retract the bolt 18 from the opening 9 and when this has been done the pressure of spring 22 will force stem 10 and lock barrel 17 to the left until the inner edge 28' of the slot 28 engages the stop pin 20 at which time further movement of the stem and barrel is arrested with the parts disposed as in Figure 4. The aforesaid movement of the stem from the position shown in Figure 2 to that shown in Figure 4 is not sufficient to bring the sloping surface 12 into engagement with the spring 16 and hence during this movement of the stem there will be no change in the position of the contact 15 so that the ignition circuit is still open when the parts assume the position shown in Figure 4. In order to permit the stem and the lock barrel to be moved from the position shown in Figure 4 to the switch closing position shown in Figure 6 it is necessary that the switch control sleeve 24 be rotated in a counter clock-wise direction relative to the lock barrel 17 so as to bring the extension 29 of the slot 28 over the inner end of the recess 21 and when this has been done the lock barrel and stem are free to move further to the left under the influence of spring 22 until the pin is engaged against the inner end of the extension 29 as shown in Figure 6. In this connection it will be noted that as the rotation of the switch control sleeve 24 from the position shown in Figure 4 to that shown in Figure 6 causes the opening 27 at the outer end of the sleeve to move out of registration with the key-hole 27 it is necessary that the key be removed from the latter before such rotation of the sleeve 24 can be effected and thus it will be seen that removal of the key from the lock is a compulsory step in the operation of shifting the movable contact 15 from the position shown in Figure 2 to the switch closing position shown in Figure 6.

When the parts are in the position as shown in Figure 6 and it is desired to lock the switch in the open position this is accomplished by shoving the switch control sleeve 24 and the lock barrel to the right until the bolt 18 automatically enters the opening 19 and the parts will then be in the position shown in Figure 8 wherein it will be noted that the movement of the stem 11 to the right from the position shown in Figure 6 has caused the contact 15 to snap away from the contacts 14 and into engagement with the block 6. After the parts have reached the position shown in Figure 8 the sleeve is rotated in a clock-wise direction on the lock barrel 17 to return the slot 18 and its extension 29 to the position shown in Figure 2 and during this turning movement of the sleeve 24 the opening 26 is again aligned with the key-hole.

From the foregoing it will be apparent

that there is little likelihood of the key being left in my improved lock switch at any time because after inserting and operating the key to release the lock it is necessary to remove the key before the switch contacts can be shifted to circuit closing position from the locked or circuit-breaking position. After removal of the key it is necessary, prior to shifting the switch contacts to circuit breaking position to operate the switch control sleeve 24 or device of the restraining means from the position shown in Figure 2 to that shown in Figure 6 and in the latter position of the sleeve, the outer wall 25 covers the key hole slot 27 and serves to prevent reinsertion of the key until the switch has been returned to the locked position and in the latter position of the switch the key will not ordinarily be inserted except for the purpose of opening the switch in the process of which the key must be removed so that there is very little danger of the key being inadvertently left in the lock at any time. The important advantage resulting from this or any other arrangement embodying my invention is that it increases the efficiency of the theft protection afforded by the lock and enables a lower insurance rate to be obtained for cars equipped therewith.

Having thus fully described my invention it will be understood that I reserve the right to resort to any such changes in the construction and arrangement of parts as may prove desirable providing that the same do not depart from the spirit and scope of the invention as defined in the appended claims.

It will also be understood that my invention is not limited to the application herein set forth but may be adapted in its broadest aspect to various types of locks other than electrical switch locks and the claims are to be construed accordingly.

From the foregoing it will be clear that after the key has been employed to release the locking mechanism and removed from the lock it is impractical to reinsert the same until after the locking mechanism has been returned to locked position.

50. What I claim is:

1. A switch lock including a key releasable locking mechanism for securing the switch contacts in one position, and means arranged to compel removal of the key after release of the locking mechanism as a necessary precedent to shifting of the switch contacts from the locked position.

2. A switch including key releasable locking means for securing the switch contacts in one position, means for automatically shifting the switch contacts from locked position when the locking mechanism is released through the agency of said key and a restraining device functioning to render the last named means ineffective as long as the

key is permitted to remain in the locking mechanism subsequent to release of the latter, said restraining means being operable, upon removal of the key, to a position permitting shifting of the switch contact from the locked position.

3. The combination of a switch, a key releasable lock mechanism for securing the switch in circuit closing position, a releasing key engageable with said locking mechanism, means for automatically opening the switch upon release of said locking mechanism, and restraining means functioning, on release of the locking mechanism, to prevent opening of the switch while the key remains in the lock, said restraining means being held against displacement to an inoperative position by the key when the latter is engaged in the lock.

4. The combination of a switch including a contact actuator operable to either of two contact shifting positions for opening and closing the switch, key releasable locking means for securing said actuator in one of said positions, spring means for shifting said actuator to the other position thereof on release of the locking mechanism, and displaceable means serving, in the locked position of the switch, to limit movement of the actuator under the influence of said spring and to such an extent as to render the latter ineffective for shifting the actuator to the extent necessary to effect a change in the position of the switch contacts, said means being held against displacement to an inoperative position by the key when the latter is engaged in the lock.

5. The combination of an element movable to either of two positions, key releasable means for locking said element in one position, and means arranged to compel removal of the key from the locking means subsequent to release of the latter and as a necessary step in completing shifting of said element from the locked to the other position to which said element is intended to be moved.

6. The combination of an element shiftable to either of two positions, means acting automatically to lock said element in place when the latter is moved to one of said positions, a removable key engageable with said means for releasing same, displaceable means arranged to limit the extent to which said element may be moved from the locked position on release of the locking means, said displaceable means being shiftable to an inoperative position only upon removal of the key, and serving, when disposed in inoperative position, to permit shifting movement of said element from locked position to be completed.

7. An electric switch, comprising, in combination, a lock including key releasable locking mechanism, and a rotatable member

associated with said lock and operable to effect opening and closing of the said switch, which member when the said switch is in closed position operates to close the 5 key hole of the lock.

8. A switch lock including a locking mechanism for locking the switch in open position, said mechanism being key releasable by a key, and means operating after 10 the release of the locking mechanism and after the removal of the key from the lock and the closing of the switch to prevent reinsertion of the key into the lock until after the return of the locking mechanism into 15 locked position.

9. In an electric switch comprising contacts which are relatively movable into closed and open positions to close and open 20 an electric circuit, the combination of a shifting device for effecting relative movement of said contacts into closed or open position, a lock including a key releasable locking mechanism for maintaining the contacts in open position, and a control device 25 operable, after release of said locking mechanism and removal of the key from the lock, to permit movement of said shifting device to cause relative movement of the said contacts into closed position, and the said device thereafter operating until the return of 30 said locking mechanism to locked position to prevent insertion of said key into the lock.

10. In a switch, the combination of a 35 shiftable contact, an actuator for shifting

the said contact into open and closed positions, a lock mounted to be moved inwardly and outwardly with respect to the said actuator to control the inward and outward movements of the latter, the said lock including 40 a locking mechanism for locking the actuator in one position, a control device rotatably mounted upon the said lock, and means cooperating with the said control device to control the inward and outward 45 movements of the said lock.

11. The combination of a switch, a key releasable lock for securing said switch in open position, a member arranged to compel movement thereof to a key hole covering 50 position, subsequent to release of the lock, in order to effect closing of the switch and means functioning, on closure of the switch, to retain said member in key hole covering position until the switch is returned 55 to and locked in open position.

12. A switch lock including a locking mechanism for locking the switch in open position, said mechanism being releasable by a removable key, and means requiring to 60 be operated to a predetermined position subsequent to release of the lock in order to permit closure of the switch, said means being arranged for operation to said predetermined position only upon removal of the 65 key from the lock and serving, on closure of the switch, to prevent reinsertion of the key into the lock until after the switch is returned to and locked in open position.

WILSON HEMINGWAY, JR.
